SON, OF BRIER HILL, PENNSYLVANIA.

AGITATING AND DUMPING BUCKET.

Specification of Letters Patent. Patented July 25, 1922.

1 filed March 28, 1922. Serial No. 547,504.

JOHNSON, a residing at Fayette and invented new agitating and he following ins for hand- materials, and ing and dump- tributed to various points of the structure being erected. Bucket 1 is mounted in a suitable frame 2 provided with U-shaped guide brackets 3 which fit about guide rails 4 secured in any suitable or preferred manner in tower 5. A cable 6 is secured at one end, at 7, to a beam 8 at the top of the tower and passes over a crown sheave 9 and a guide sheave 10, this cable being wound upon a drum in a known manner for raising and lowering frame 2.

The invention efficient means attach of con- a bucket to discharge are bucket so as f proper con- ning of the to provide be automatic- any one of objects will option.

e bucket and tower being : the station- apparatus; f the bucket in section, of pair of agi- h one of the if one of the side view of showing the ent into dis- substantially to Figure 8 rts when the rts are adapt- tower which table or pre- g discharged bin or chute ture is dis- A securing plate 11 is secured to the inner face of bucket 1 at each side thereof and is provided with a central hub 12 which fits into a corresponding recess in an outer plate 13 secured to the outer face of the bucket, this outer plate being provided with a sleeve 14 mounted through a bearing block 15 secured to the side rail of frame 2. A shaft 16 extends across the bucket and through sleeves 14, endwise movement of this shaft being positively prevented by means of a collar 17 secured on one end of the shaft and a bevel gear 18 secured on the other end of the shaft. The recess in plate 13 and sleeve 14 is so shaped as to provide an outwardly tapering space for reception of a suitable packing 19 which is forced tightly about shaft 16 by means of hub 12 of plate 11, the plates being forced toward each other and secured to the bucket by means of bolts 20 and nuts 21. Inner plate 11 is further provided with a plurality of outwardly projecting screw studs 22 which are adapted to pass through the bucket and corresponding openings in plate 13 and to receive securing nuts by means of which the plates may be forced toward each other. This provides a fluid tight closure about shaft 16 so as to effectually prevent leakage about the shaft, the sleeves 14 and shaft 16 providing a rockable mounting for bucket 1 and the shaft is freely rotatable in the sleeves.

A plurality of mixing blades 23 are mounted upon the shaft 16 within the bucket, these blades being disposed in pairs and the blades of each pair being secured together and to the shaft by means of bolts 24 and nuts 25, the bolts passing through blocks 26 provided at the inner ends of the blades and fitting snugly about the shaft. A counter-shaft 27 is rotatably mounted in suitable bearings at one side of frame 2 and a bevel pinion 28 is secured on this counter-shaft and meshes with gear 18. A worm wheel 29 is

secured on the upper end of shaft 27 and meshes with a worm 30 secured on the armature shaft of an electric motor 31 mounted in frame 2. An electric current is supplied to 5 this motor from any suitable source of supply by means of a cable or cord 32 which passes over a sheave 33 mounted at the top of tower 5, this cable passing beneath a sheave 34 from which is suspended a counter-weight 35 10 which operates in an enclosing and guide casing 36 secured to one side of tower 5. After passing beneath sheave 34 the cable is secured, at 37, to the top of tower 5 and is extended so as to be connected to any suitable 15 source of electrical energy. When the bucket 1 is raised or lowered in the tower the cable will be maintained under tension by counter-weight 35 thus eliminating all possibility of the cable becoming slackened to such an extent 20 as to become entangled in frame 2 or the gearing for driving the agitator. This provides simple and efficient means whereby the shaft 16 and the blades carried thereby, which constitute the agitator, may be continuously driven so as to retain the ingredients of the concrete mixture in an intimately 25 mixed condition thus insuring that the mixture, when discharged from the bucket, will be in such condition as to obtain the very best results. This cannot be done with the 30 present type of buckets used due to the fact that as the bucket is raised the vibration causes the heavier ingredients of the mixture to settle to the bottom of the bucket, the 35 lighter ingredients and the water collecting upon the top of the mixture so that when the mixture is discharged from the bucket the ingredients are not in an intimately mixed condition and the mixture is not of the 40 proper consistency. By providing means for thoroughly agitating the ingredients until the instant of their discharge from the bucket I avoid this very serious objection. While the bucket and the agitator carried thereby 45 are intended more particularly for elevating and discharging concrete which has been previously mixed in a mixer of known type, in case of necessity, or if desired, the ingredients without being mixed may be placed in 50 the bucket and the agitator will serve to thoroughly mix the ingredients by the time the bucket reaches its point of discharge. This is particularly true where the point of discharge is several stories or more from the 55 level at which the ingredients are placed in the bucket. This effects a material saving in time which is frequently of importance, as well as effecting a saving in the cost of mixing of the concrete. 60 A locking shaft 38 is rockably mounted on one side of bucket 1 in bearing blocks 39. This shaft is provided at its inner end with a rectangularly disposed locking arm 40 adapted for engagement inside of a locking 65 bracket 41 secured to the front face of the

adjacent rail 4. A tension spring 42 is secured at its lower end to a finger 43 secured to shaft 38 and, at its upper end, to bucket 1. This tension spring normally holds shaft 38 in locking position with arm 40 engaging through bracket 41 so as to positively prevent downward and forward movement of bucket 1 about shaft 16, thus locking the bucket in upright or charge receiving and retaining position. 70

A tripping arm 44 is secured on the outer end of shaft 38 and is positioned to strike the upper wall of a slotted tripping plate 45 secured by means of arms 46 to tower 5. This plate has a slot 47 for reception of the tripping arm, the upper wall 48 of which is extended inwardly to be struck by the arm during upward movement of the bucket. Contact of arm 44 with the upper wall 48 of slot 47 rocks the shaft 38 downwardly so as to withdraw locking arm 40 from bracket 41 thus releasing the bucket. When this takes place the bucket is rocked forwardly about shaft 16 by means of a dumping rod 49 slidable through a bearing block 50 secured to the side of the bucket, this rod being provided with a head 51 slidable through a bearing block 52 secured to the side of the bucket, which head is forced against bracket 41 by an expansion coil spring 53 mounted about the rod and confined between block 50 and a washer 54 mounted about the rod at the outer end of head 51. Referring to Figures 7, 8 and 9, head 51 is provided, in its inner end, with a rectangular recess 55 adapted to receive locking arm 40 when the same is inoperative position (Figs. 7 and 8). This provides simple and efficient means for holding the locking arm in substantial parallelism with, and closely adjacent to the side of bucket 1 until the bucket is returned to operative or material receiving position at which time contact of head 51 with bracket 41 forces the head outwardly so as to release arm 40 which is moved into position to engage through the bracket by means of spring 42 and shaft 48. After arm 44 is rocked downwardly so as to release the bucket the bucket is raised into substantially the position indicated in Figure 1, the arm 44 traveling outwardly in slot 47 of plate 45. During this operation the weight of the bucket is supported upon a track 56 secured to plate 45, this track being positioned to receive a 100 roller 57 carried by a bracket 58 secured to bucket 1. During the dumping operation the shaft 16 is rotated, the blades 23 materially assisting in discharging the concrete 105 mixture from the bucket. 110

In practice, the supporting structure or tower will be built to any desired height, tripping plates 45 and associated parts being placed at the various points where it is desired to discharge the concrete from 115 120 125

- 5 angle lever 45, the
10 slot 47 being so shaped
15 that when the
20 lever 59 is moved
25 into the inner edge
30 of the slot, a slight
35 displacement of the
40 lever 59 will permit
45 the bucket 1 to be
50 tilted into a discharging
55 position. When the
60 bucket 1 is tilted
65 into a discharging
70 position, the inner edge
75 of the slot 47 will
80 engage the lever 59 and
85 return the lever 59
90 to its original position
95 so that the bucket 1
100 will be returned to
105 an upright position.
110 4. In an apparatus of the character
115 described, in combination with a supporting
120 structure, a frame movable in said structure,
125 a bucket tiltably mounted in said frame,
130 means for raising and lowering the frame, a
135 locking shaft rockably mounted on the
140 bucket, co-operating means carried by said
145 shaft and the frame for releasably securing
150 the bucket in upright position, means for
155 normally holding the shaft in operative
160 position, co-operating means carried by the
165 supporting structure and said shaft for rock-
170 ing the shaft into inoperative position when
175 said bucket reaches a predetermined point in
180 its upward travel, the means carried by the
185 shaft and said structure acting to return the
190 bucket to upright position as it is lowered,
195 and means for tilting the bucket into dump-
200 ing position acting to hold said shaft in in-
205 operative position during the dumping opera-
210 tion and to release the shaft upon return
215 of the bucket to upright position.
220 5. In an apparatus of the character de-
225 scribed, in combination with a supporting
230 structure, a frame mounted in said structure
235 for vertical movement, means for raising and
240 lowering said frame, a bucket tiltably mount-
245 ed in the frame, a locking member carried
250 by the frame, a locking shaft rockably
255 mounted on the bucket, a locking arm se-
260 cured on said shaft and disposed for engage-
265 ment with said member, means for normally
270 holding the shaft rocked into operative po-
275 sition with the arm in engagement with the
280 locking member, a tripping arm secured on
285 the shaft, a tripping plate secured on said
290 structure, the plate being slotted and the up-
295 per wall of the slot being extended into the
300

path of movement of the tripping arm during upward travel of the bucket so as to rock the shaft into inoperative position and release the bucket for dumping, means for tilting the bucket into dumping position when the shaft is rocked into inoperative position and for holding said locking arm in inoperative position during the dumping operation and releasing the arm upon return of 10 the bucket to upright position, the tripping

arm and said tripping plate co-operating to return the bucket to upright position upon lowering of the bucket from dumping position, and means for optionally closing the slot in said plate so as to bridge the inner 15 end thereof and prevent contact of said tripping arm with the upper wall of the slot.

In testimony whereof I affix my signature.

GEORGE JOHNSON.
